UNITED STATES PATENT OFFICE.

GEORGE FLETCHER, OF BROOKLYN, NEW YORK.

HOISTING-GEAR.

SPECIFICATION forming part of Letters Patent No. 429,308, dated June 3, 1890.

Application filed March 10, 1890. Serial No. 343,402. (No model.)

To all whom it may concern.

Be it known that I, GEORGE FLETCHER, a citizen of the United States, residing at Brooklyn, in the county of Kings and State of New York, have invented certain new and useful Improvements in Hoisting-Gears, of which the following is a specification.

The various hand hoisting-gears now in use, both of the differential and worm-gear forms, are necessarily slow of operation in order to obtain the required power; but it is very often desirable to have a faster motion for the purpose of quickly overhauling the tackle or to drop the weight being lifted rapidly into a required position. The object of my invention is to meet this requirement; and it consists of a mechanism which can be attached to any of the usual forms of hoisting-gears.

The accompanying drawing shows an elevation of a common form of hoisting-gear with my improved mechanism in section attached.

The main driving-shaft *a*, which is operated by the power hoisting-wheel *A*, is extended through the opposite side of the frame *b* and carries a pinion *e*. A stud *s* is fixed in the framing *b*, and upon it is mounted a large gear-wheel *W*, which meshes with the pinion *e*. On the periphery of the large wheel *W* is formed a groove *v* to receive the chain or rope by which it is operated.

In the drawing I have shown the wheel *W* in the form of an interior gear; but it is evident that a gear-wheel of the ordinary form, with the teeth on the outer edge, may be used where desired.

For hoisting heavy weights the gear is operated, as usual, by the chain *C* and wheel *A*; but when it is desired to overhaul the chain *X* rapidly, either for adjustment or for the purpose of quickly lowering the weight that has been hoisted, the gear is operated by the wheel *W* by means of a chain or rope working in its groove *v*. It is evident that with the speed combination of the gears *W* and *e* the shaft *a* will be revolved much faster than would be possible with the wheel *A*, and the speed of the chain *X* correspondingly increased. The smaller power exerted by this speed-gearing is of no consequence, as it is only intended for overhauling the chain *X* or rapidly lowering a weight that has already been lifted by means of the wheel *A*. As my improved attachment does not in any way interfere with the operation of the gear in the usual manner, there is no necessity for throwing it out of gear when not in use.

What I claim, and desire to secure by Letters Patent, is—

In a hoisting-gearing, the combination of a small pinion fixed upon the main driving-shaft with a large gear-wheel having a groove in its periphery and mounted on a stud fixed in the frame of the apparatus and meshing with said pinion, said gear being operated by an endless chain or rope working in said groove in its periphery, substantially as and for the purpose set forth.

GEORGE FLETCHER.
